Howard S. Smith,
His ATTORNEY

UNITED STATES PATENT OFFICE

HERMAN L. BROWN, OF GREENVILLE, OHIO

QUICK DETACHABLE TOP LIFT FOR HEELS

Application filed August 14, 1931. Serial No. 557,017.

This invention relates to improvements in quick detachable top lifts for heels.

It is one of the principal objects of my invention to provide simple and convenient means for quickly detaching a top lift from a shoe heel and replacing it with another.

This quick method of changing top lifts will prolong the life of the shoe to which it is applied, by keeping it in better condition through frequent renewals of the top lifts of the heels.

Because it encourages frequent changes of the top lift, the method is also an aid to correct foot posture by keeping the shoes nearer their original shape at all times.

It is another object of my invention to provide a metal plate which covers all of the area of the surface of the heel adjacent to the top lift, thus keeping that surface in good condition for the attachment of a new top lift.

Another object of my invention is the provision within the top lift of a pin which is removable to make the removal of the top lift an almost instant operation.

Other important and incidental objects will be brought out in the following specification and particularly set forth in the subjoined claims.

In the accompanying drawing illustrating my invention, Figure 1 is a side elevation of a shoe heel having my quick detachable top lift applied thereto. Figure 2 is a sectional view through a shoe heel equipped with my detachable top lift. Figure 3 is a perspective view of the attaching mechanism applied to the top lift. Figure 4 is a perspective view of the lock plate attached to the heel immediately above the top lift. Figure 5 is a bottom view of a shoe heel, showing the top lift being applied. And Figure 6 is a sectional view taken on the line 6-6 of Figure 2, showing the locking fingers and locking pin.

Referring now to the accompanying drawing for a complete description of my invention, the numeral 1 indicates a conventional shoe heel from which a top lift 2 is separate. (See Figures 1 and 2.)

Secured to the lower face 3 of the heel 50 as shown at Figure 4, is a metal plate 4 hav-

ing the same profile as the face 3 and attached thereto by nails 5. This plate 4 covers all of the area of the surface of the heel adjacent to the top lift, thus keeping that surface in good condition for the attachment of a new top lift.

Projecting downwardly from the plate 4, and oppositely disposed on its longitudinal center line, are two locking fingers 6-6. These fingers 6-6 are inclined downwardly from the plate 4 and then upwardly to form abrupt shoulders 7. Beyond the shoulders 7 the free ends 8 of the fingers 6-6 are again inclined downwardly.

Between the fingers 6-6 and adjacent to their inner ends are two clamp receiving holes 9-9, while at the front of the heel, the plate 4 and heel 1 are provided with a rectangular slot 10. (See Figures 2, 4 and 6.)

Referring to Figure 3, I have shown the locking mechanism applied to the inner face of the top lift 2, and comprising a metal plate 11 secured to the top face of the top lift 2 by nails 12. The plate 11 has a central circular depression 13 that is received by a like depression 14 in the top lift.

Formed perpendicularly from the face of the depression 13 are two opposite clamps 15 whose outer free ends 16 are formed at right angles with their inner ends.

Also punched from the bottom of the depression 13, and oppositely disposed on its longitudinal center line, are two clearance holes 17-17.

Formed in the face of the plate 11 on opposite sides of the depression 13 and in alignment with the holes 17-17 are two tunnel lugs 18-18 to receive between them and the outer face of the plate 11, a locking pin 19. (See Figure 3.)

The pin 19 is of triangular cross section as shown in Figure 6 and has at its forward end an angular head portion 20.

The plate 11 as attached to the top lift 2 is covered with a thin piece of leather 21 having a central aperture 22 to clear the depression 13. (See Figures 3 and 6.)

Now, when it is desired to place a new top lift on a heel equipped with the plate 4, the top lift, as shown at Figure 3 is placed

over the heel plate 4 as shown by the dotted outline of the top lift at Figure 5. When in this position the free ends 16 of the clamps 15-15 will enter the holes 9-9 and the locking pin 19 will be adjacent the free ends 8 of the locking fingers 6-6, the pin 19 being slightly withdrawn as shown at Figure 3.

As the top lift is rotated to its proper position in alignment with the heel 1, the pin 19 will be engaged by the shoulders 8 of the locking fingers 6-6 and the clamps 15-15 will enter the holes 9-9 to rightly draw the top lift against the heel.

As a final operation the head portion 20 of the pin 19 is forced into the recess 10. Now, with the shoulders 7 of the locking fingers 6-6 engaging the wide face of the pin 19 as shown at Figure 6, and with the head of the pin in the recess 10, it is impossible to loosen the top lift, the clamps 15-15 through their engagement with the holes 9-9 further securing the top lift to the heel proper.

When the top lift becomes worn, it is only necessary to withdraw the pin 19 from the latter, and by a slight counter movement of the top lift to that previously described, it may be removed and discarded.

The replacing of the top lift is of such simple procedure that it can be accomplished by anyone in a moment's time, thus adding greatly to the value and appearance of any shoe equipped with my time and money saving invention.

Having described my invention, I claim:

1. The combination with a shoe heel, of a plate secured to, and covering the bottom face area of, said heel, locking fingers projecting downwardly from said plate approximately on the longitudinal center line thereof, said plate formed with clamp receiving holes adjacent said locking fingers, a top lift, a plate secured to the upper face of said top lift, hook clamps formed on said top lift plate to enter the clamp receiving holes in the heel plate, a pair of tunnel lugs on the longitudinal center line of the top lift plate, and a locking pin inserted through the tunnel lugs for engagement by the locking fingers when the hook clamps engage in the clamp receiving holes of the heel plate, said pin adapted to be withdrawn axially, outwardly by its angle portion to permit a quick detachment of the top lift from the heel.

2. The combination with a shoe heel, of a plate secured to, and covering the bottom face area of, said heel, two locking fingers projecting downwardly from said plate approximately on the longitudinal center line thereof, said plate formed with clamp receiving holes adjacent said fingers, a top lift, a plate secured to the upper face of said top lift, hook clamps formed on said top lift plate to enter the clamp receiving holes in the heel plate, a pair of tunnel lugs formed on the longitudinal center line of the top lift plate between the

hook clamps thereon, said top lift plate formed with two holes opposite the locking fingers on the heel plate when the top lift is applied thereto, and a locking pin inserted through the tunnel lugs for engagement by the locking fingers when the hook clamps engage in the clamp receiving holes of the heel plate, said pin adapted to be withdrawn longitudinally to permit a quick detachment of the top lift from the heel.

3. The combination with a shoe heel, of a plate secured to, and covering the bottom face area of, said heel, a pair of locking fingers projecting downwardly from said plate approximately on the longitudinal center line thereof, said plate formed with clamp receiving holes adjacent said locking fingers, a top lift formed with a central recess in its upper surface, a plate having a depressed portion adapted to fit in said recess, hook clamps formed on said top lift plate to enter the clamp receiving holes in the heel plate, a pair of tunnel lugs formed on the longitudinal center line of the top lift plate, one at each end of the depressed portion thereof, said plate formed at the bottom of its depressed portion with two holes, one opposite each locking finger when the top lift is applied to the heel, and a locking pin having a head, said heel plate having a recess in its straight edge to receive said head, said pin adapted to be inserted through the tunnel lugs for engagement by the locking fingers when the hook clamps engage in the clamp receiving holes of the heel plate, said pin adapted to be withdrawn axially, outwardly by its angle portion to permit a quick detachment of the top lift from the heel.

In testimony whereof I have hereunto set my hand this 12th day of August, 1931.

HERMAN L. BROWN.
